(57) **CLAIM**

The ornamental design for a charger, as shown and described.

DESCRIPTION

FIG. 1 is a front perspective view of a charger showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top elevational view thereof;

FIG. 7 is a bottom elevation view thereof;

FIG. 8 is a rear elevational view thereof;

FIG. 9 is a second rear perspective elevational view thereof; and,

FIG. 10 is a third rear perspective elevational view thereof.
